His ATTORNEYS.

UNITED STATES PATENT OFFICE.

WILLIAM P. WITHEROW, OF PITTSBURGH, PENNSYLVANIA, ASSIGNOR TO WITHEROW STEEL CORPORATION, OF PITTSBURGH, PENNSYLVANIA, A CORPORATION OF PENNSYLVANIA.

AXLE BLANK.

Original application filed December 30, 1921, Serial No. 525,979. Divided and this application filed June 25, 1927. Serial No. 201,316.

Figure 1 is a perspective view of one form of a rolled leader or blank ready for die rolling.

Figure 2 is a side elevation of a portion of a series of one form of axle blanks as they emerge from the die rolling,

Figure 3 is a top plan view of one of the blanks shown in Figure 2,

Figures 4 and 5 are cross sectional views 10 on the lines IV—IV and V—V respectively of Figure 2,

Figures 6, 7 and 8 are views similar to Figure 2 showing other forms of die rolled axle blanks embodying my invention,

15 Figure 9 is a cross sectional view on the line IX—IX of Figure 8,

Figure 10 is a side elevation of the ends of two axle blanks having a gating connecting the same, and

20 Figure 11 is a top plan view of the gating shown in Figure 10.

My invention relates to the manufacture of vehicle axles, and more particularly the front axles of automotive vehicles.

25 This application is a division of my application Serial No. 525,979, filed December 30th, 1921; which application eventuated in United States Patent 1,656,846, dated January 17th, 1928. Automotive vehicle axles are

30 generally of two kinds, one in which the end of the axle itself is split and formed into forks, for receiving a stub axle, while in the other, the forked portion is on the stub axle, this forked portion cooperating with a bored 35 boss at the end of the axle. This latter form is termed the "reverse Elliott type".

Heretofore in making the type of axle having forked ends, the end portions of the original blank have been split and formed 40 into forks, and the main body of the axle has then been forged to shape.

45 My invention relates to the formation of such axles from a rudimentary recessed leader or preliminary blank. This preliminary blank, which may have any one of a large number of shapes, is preferably of uniform cross-section having a cross-sectional shape corresponding in a rudimentary way to the cross-sectional shape of a portion of the finished die-rolled blank. For example, these

50 front axles as now made usually have a central portion of I-beam cross section, this I-beam either being of the same depth or vary-

ing depth between the points of attachment for the springs. In making such axles, my 55 leader is preferably of rudimentary I-beam shape. This leader of uniform cross-section is then rolled in die rolls to form a connected series of axle blanks, which are then cut, sawed or sheared apart. If desired, the ends 60 may be cut to length, or the blanks may be initially rolled from center to center with the ends directly connected or connected by a suitable gating, as illustrated more particularly in Figures 10 and 11. By the expression "from center to center" as used herein, I mean from a given point in one blank to a 65 corresponding point in an adjacent blank, to provide a constant distance therebetween, or from a given point in one blank to another 70 point on the same blank. The purpose, of course, is to give substantial uniformity in successive blanks. After the individual blanks are separated from the series the flash formed in the die-rolling is trimmed or 75 sheared off, the blank then being ready for the final operations. These final operations may consist of machining certain portions and in most cases of forging the end portions to the desired final shape. 80

The dies for making these axle blanks are, of course, shaped to give the desired section for the central portion, form the spring seats, if required, and make suitably shaped end portions for the blanks, which are thereafter 85 reshaped, as desired.

This application covers the blanks formed by the die rolling process. The parent application above referred to describes and claims the method of forming the blanks from a 90 leader which is of rudimentary recessed shape. The die rolled axle has numerous advantages over axles made by other processes due to the fact that the rolling and extrusion which are effective in the die rolling pass impart to the metal a grain structure which is peculiarly useful in articles of this character. The blank may take different forms, according to the type of axle desired, the type of 95 spring attachment and so forth, but will contain the features embodied in my broader claims.

In Figure 1 there is illustrated one form of leader adapted to be rolled in accordance with the present invention, and having a rudimentary I-beam section for producing front 100

axles of the I-beam type as referred to. In Figures 2, 6, 7 and 8 I show a part of the string of connected blanks of this type coming from the die rolls.

5 In Figure 2 there are illustrated portions of two blanks each having a central I-beam portion 2 shown as of varying cross-section, the depth of the I-beam increasing toward the thickened or boss portions 3 shown in section in Figure 4, where the spring attachments are made. Beyond the portions 3, there are short I-beam portions 4 shown in section in Figure 5, which gradually merge into solid end portions 5, preferably of rectangular form in cross-section. Flash or fins 6 are formed on the intermediate portions of the blank during the die-rolling operation, the amount of the flash varying in accordance with the shaping and reducing operations to 15 which the leader is subjected during the rolling. As will be clear from the drawings, the flash has a well defined line of junction with the axle. In die-rolling, a string of these blanks will come from the rolls, the blanks 20 being then sheared apart and trimmed at the ends to the correct length, or directly sheared to exact length when the blanks are rolled from center to center.

Such axle blanks, after trimming, may be 30 furnished to the manufacturer who splits and forks the solid end portions to make the fork type of axle, and machines certain portions, such as the portions 3, 3. These blank ends may, however, be forged into bosses instead of yokes in making the reverse Elliott 35 type.

In Figure 6 there are illustrated portions of two blanks generally similar to those shown in Figure 2. In this form, however, 40 the central portion 2^a of each blank is of uniform cross-section and each entire blank is rolled to finished dimensions. These blanks have bosses 3^a for the attachment of the springs, and short I-beam sections 4^a, 45 which merge into solid bosses 5^a ready to be machined and bored, for axles of the reverse Elliott type, after the blanks are separated and the flash trimmed away. The bosses 3^a may be similarly re-shaped or machined.

50 In Figure 7 the central portion 2^b of each blank is shown of I-beam form, this extending into lumps 7, instead of finished bosses. Beyond these lumps there may be partial finished I-beam portions 4^b which merge into square or rectangular solid end portions 5^b. In this case the I-beam portion after trimming off the flash 6^b is in finished condition and the lumps form stock from which 60 the spring pads or bosses for spring connection or support are made. The end portions may be forged into yokes or bosses depending on the type of axle desired.

65 In Figure 8 I show still another form of blank having the finished I-beam central

portion 2^c terminating in lump stock 7^c with I-beam portions 4^c outside the lump portions and extending to flattened eye portions 5^c illustrated in section in Figure 9. With this form, the webs 8 of the eyes are punched out and the eyes opened to form yokes which are then forged, the lump portions being either reforged, machined or both to provide the spring pads or spring bosses.

70 In Figures 10 and 11 the adjacent ends 5^d of the axle blanks are illustrated as being connected by a gating 10. In many instances it may be desirable to roll the strings of blanks with such a gating, particularly in rolling to finished dimensions or from center to center. In such cases, the gating indicates the exact points at which to separate the blanks. Such a gating is also very effective in rolling blanks more particularly of the forms shown in Figures 2, 3 and 7, as it 80 gives the rolls a bite on the leader and prevents slipping thereof when rolling the rectangular end portions. This insures accurate rolling, and minimizes the number of blanks which must be scrapped.

90 In all the forms it will be understood that the die rolls turn out a connected integral string or series of these blanks which are then separated from each other, the blanks either being directly connected end to end or having a gating or portion to shear away between their ends. It will be noted that in each form there is a portion or portions of the axle rolled to finished dimensions and that in some of the cases forging of parts 95 is necessary as well as machining, while in other cases, such as that of Figure 6, the axle requires only machining after the flash is trimmed away.

100 During the rolling step the articles are extruded in a greater or less amount, depending upon the amount of reduction. In this respect my invention differs materially from processes wherein bearing balls or the like are pressed out of a strip. Such operations are essentially continuous pressing schemes and are not true rolling or extrusion processes.

110 The advantages of my invention will be obvious to those skilled in the art, since an inexpensive semi-finished product is afforded, thereby greatly reducing the amount of after work thereon. In some cases reforging may be entirely eliminated. The present invention also reduces the hammer size 120 required for the forging operations, insures a more uniform product having a particularly desirable grain structure, and increases production.

125 Many changes may be made in the form and size of the axle, depending on the type desired, and other changes may be made without departing from my invention. The broad method may also be applied to making blanks other than axle blanks, as disclosed 130

in my Patent 1,572,343, dated February 9th, 1926.

I claim:

1. As a new article of manufacture, a die 5 rolled axle blank of varying cross sectional shape, a portion of the axle blank being of I-beam cross section, the blank having spring attachment portions and solid end portions, the blank having a flash zone alongside the 10 I-beam portions.
2. As a new article of manufacture, a die 15 rolled axle blank having an intermediate portion of varying I-beam cross section, the I-beam portion merging into solid end portions and having spring seats, the blank having a flash zone alongside the I-beam portions.
3. As a new article of manufacture, a 20 string of die rolled axle blanks having middle recessed portions of substantially final dimensions and having end portions adapted for reworking, the blanks having a flash on at least one side thereof, the flash varying

in amount along the blank, the portions of the string lying between the middle portions of 25 adjacent blanks being materially thicker than the flash.

4. As a new article of manufacture, a string of die rolled axle blanks having middle recessed portions of substantially final 30 dimensions, end portions adapted for reworking, and spring attaching portions between the middle recessed portions and the end portions, the blanks having a flash on at least one side thereof, the flash varying in amount 35 along the blank.

5. As a new article of manufacture, a 40 rolled axle blank of varying cross sectional shape having a recessed portion and having spring attaching portions and end portions, the blank having a flash zone alongside the recessed portion.

In testimony whereof I have hereunto set my hand.

WILLIAM P. WITHEROW.
